Specification of Letters Patent.

Patented Oct. 17, 1916.

Application filed May 18, 1915. Serial No. 28,942.

To all whom it may concern:

Be it known that I, JOHN GEORGE HANSON, a citizen of the United States, residing at Osakis, in the county of Douglas and State of Minnesota, have invented certain new and useful Improvements in Sanitary Receptacles, of which the following is a specification.

This invention relates to an improvement in sanitary receptacles or containers, and the object is to provide means for supporting and covering articles such as parts of a cream separator to prevent insects from coming in contact with the parts, and at the same time allowing fresh air to come in contact with the articles or parts.

The invention consists of certain novel features of construction and combinations of parts which will be hereinafter described and pointed out in the claim.

In the accompanying drawings, Figure 1 is a perspective view showing the cover in a raised position; and Fig. 2 is a transverse vertical sectional view.

A, represents the base, and B represents a frame connected to the base by means of hinges 1.

The frame B has a covering of screen material 2 connected thereto, which is somewhat arch shape in cross-section. A molding 3 extends around the frame B for covering the ends or edges of the screen where it is connected to the frame.

Guide-strips 4 extend transversely of the base A for guiding the cover into place, the strips engaging the inner surface of the frame B of the cover when the cover is swung to closed position.

Hooks or hangers 5 are connected to the base, by means of screws 6. These screws 6 are intended to be screwed into a building or other support for fastening the base, so that the base will hang and lie against a vertical wall or surface.

Mounted upon the hooks or hangers are parts of a cream separator, which it is desired to dry and air by allowing fresh air to come in contact therewith, without permitting insects to come in contact with the parts.

From the foregoing it will be seen that I have provided a simple attachment for supporting articles to be dried and aired, without subjecting the articles to contact by insects and the like.

I claim:

The combination with a base adapted to be fastened to a wall, of a frame hinged to the base, a screen fabric connected to the frame, said screen fabric consisting of two substantially parallel end members and a circular strip connected at its edge with the edges of the end members, means on the base adapted to engage the inner surface of the frame when swung over and upon the base, hooks mounted on the base for supporting the article to be protected, and removable means for connecting the hooks to the base and for fastening the base to a support.

In testimony whereof I affix my signature in the presence of two witnesses.

JOHN GEORGE HANSON.

Witnesses:

A. A. LUDWIGS,
D. B. McCLEERY.
